(57) **CLAIM**

The ornamental design for a child's feeding spoon, as shown, and described.

DESCRIPTION

FIG. 1 is a perspective view of the child's feeding spoon; FIG. 2 is a top view thereof;

FIG. 3 is a bottom view thereof;

FIG. 4 is a right side view thereof (with the left side a mirror image thereof);

FIG. 5 is a rear elevation view thereof; and,

FIG. 6 is a front elevation view thereof.

The broken lines represent structure and form no part of the claimed design.
